G. F. MILES ET AL.
WIND AND RAIN SHIELD.
FILED JULY 10, 1922.

UNITED STATES PATENT OFFICE.

GEORGE F. MILES, OF NEW YORK, N. Y., AND SANFORD EVANS, OF BIRMINGHAM,
ALABAMA; SAID EVANS ASSIGNOR TO SAID MILES.

WIND AND RAIN SHIELD.

Application filed July 10, 1922. Serial No. 573,856.

To all whom it may concern:

Be it known that we, GEORGE F. MILES and SANFORD EVANS, citizens of the United States of America, respectively, residing at New York, N. Y., and 1320 N. 24th Street, Birmingham, Jefferson County, Alabama, have invented new and useful Improvements in Wind and Rain Shields, of which the following is a specification.

This invention relates to improvements in wind and rain shields for use with rapidly moving vehicles, the purpose being to provide means for affording an open or free line of vision for the operator so that rain or snow will not drive therethrough. It is in certain important respects an improvement on the structure set forth in United States Letters Patent 1,416,112 dated May 16, 1922, as will be seen by reference to the following specification and an examination of the accompanying drawings in which

Figure 1 is a front view of one end of our improved wind shield as it would appear in use.

Figure 2 is a side elevation partly in section.

Figure 3 is a similar view somewhat reduced in size and showing the parts in a slightly different position.

Figure 4 is a side view of a modification.

Figure 5 is a sectional detailed view relatively enlarged.

We have illustrated in the accompanying drawings only such parts as are necessary for a clear understanding of the invention.

1 represents the usual cowl, or dashboard portion of a vehicle. 2 represents conventionally the usual top or roof. 3 represents one of the side wind shield standards, two of which are provided, one on each side of the vehicle. Each standard 3 may be independent of the top, as in a touring car, or may be permanently connected thereto as in a closed car such as sedan or limousine. 4 is a forwardly projecting shade, or the like, which may be carried by the top 2, as in Fig. 2, or may be pivoted to the upper end of the standard 3, as in Fig. 4. 5 is a brace pivotally connected at one end to the forward portion of the shade element 4, while the other end of said brace may be provided with a slotted slide 5^a or equivalent device which bears against the adjacent side of standard 3 and is held by a suitable clamp

fastening 6 in any desired position of adjustment. Two of such braces are provided. By moving the slide 5^a up or down the forward portion of the shade 4 may be raised as in Fig. 2, or lowered as in Fig. 3. In no event does the rear end of the brace 5 project to any objectionable degree to the rear of the standard 3. 7 is the usual lower wind shield section arranged between the side standards 3. 8 is an upper shield section which performs the dual function of a shield and a deflector. This shield section 8 is pivoted to swing at its upper edge from beneath the shade 4 and may be locked in any desired angular position by the clamping device 9. 10 is a co-acting curved deflector member arranged at the under side of the shade 4 near to the forward edge. The lower edge of deflector 10 preferably bears against the forward side of the upper wind shield member 8 and said deflector 10, while being preferably sufficiently rigid to withstand wind pressure is also preferably sufficiently flexible so that it will permit the wind shield 8 to be angularly adjusted. The effect of the curved deflector 10 is to start a draft down along the face of the shield 8 without baffling the same so that the downwardly directed current of air will build up in velocity as it proceeds down the face of shield 8 until it reaches such high speed that it will prevent rain or snow from passing into the car through the open clear vision space between the upper edge of the lower wind shield section 7 and the lower edge of the upper shield section 8. This open clear vision passage is conventionally illustrated in Figs. 2 and 3 by dotted lines. By this arrangement we are able to employ effectively a flat uncurved glass for the upper wind shield section 8. The curved co-acting deflector 10 at the upper part of and in front of the shield 8 will start a draft that will build up in velocity more effectively than a deflector that is wholly flat, or uniform throughout its entire area, the latter form being shown in Fig. 1 of the aforesaid patent. In Fig. 4 we have indicated the upper shade element 4 as being pivoted to the upper end of the standards 3 and we have also indicated conventionally a clamping device 11 for controlling the hinged joint.

It will be apparent from the above that the apparatus is applicable to all types of

- cars; also that it has a wide range of adjustment; also that it may be economically manufactured. The curved deflector element 10 not only serves to start the draft in the manner aforesaid but it also covers any opening between the upper edge of the shield element 8 and the lower side of the shade 4 thereby avoiding the necessity of a separate packing along this line.
- 10 The shield sections 7 and 8 are preferably transparent. The member 10 may be made of any material transparent or otherwise. The shade element 4 may likewise be made of any suitable material. In the form shown 15 the lower wind shield section 7 appears as inclined back at an angle which makes it necessary to create a powerful down draft to overcome tendency of the ascending draft created thereby. We have found that by the 20 co-operation of the elements 10 and 8 a sufficiently strong current of air in the downward direction is generated to effectively overcome said tendency and to prevent rain and snow from driving through the open 25 clear vision space.

The deflector element 10 may rest loosely against the upper section 8, as shown in Figure 2, its own resiliency holding it in place, or if desired the upper part of the frame of the section 8 may be provided with a row 30 of buttons, one of which is indicated at 12 in Figure 5 and the deflector 10 may be provided with a corresponding row of co-acting sockets, one of which is indicated at 14 in 35 Figure 5. By this button and socket fastening means the deflector 10 may be detachably secured to the section 8 so that even if the material of the deflector 10 is comparatively light, the fastenings aforesaid will 40 serve to hold the deflector 10 in such a manner that it will present a properly curved deflecting surface for the purpose of starting the draft.

The deflector 10 may be made of any material stiff enough in itself to maintain a 45 properly curved form, or if not, the said deflector may be suitably reinforced in any desired way to preserve said curved form while being subjected to heavy wind pressure. Again, by this construction the lower 50 part of said deflector will follow and bear against said upper section 8 in its various positions of angular adjustment.

What we claim is:

- 55 1. In a device of the character described, a lower shield section, an overhead forwardly projecting shade element, a substantially flat transparent upper shield section suspended below said shade and forward of the lower section, means whereby said upper section may be arranged at a rearwardly inclined angle with its lower edge above the upper edge of the lower section, and a curved means co-acting with the upper section 60 and arranged in front of the upper part of

the same to start a downwardly directed current of air along the substantially flat surface of the upper section.

2. In a device of the character described, an overhead shade element, a substantially flat wind shield element suspended therefrom and near the forward edge thereof, means for securing the same at an angle whereby it will operate as a deflector, and a co-acting deflector element extending underneath the shade element and arranged adjacent the upper part of said shield element and in front of the latter, said co-acting deflector element being curved to start a draft of air down the face of the shield as the same is propelled 75 forwardly.

3. In a device of the character described, an overhead shade element, a substantially flat wind shield element suspended therefrom and near the forward edge thereof, means for securing the same at an angle whereby it will operate as a deflector, and a co-acting deflector element extending underneath the shade element and arranged adjacent the upper part of said shield element and in front of the latter, said co-acting deflector element being curved to start a draft of air down the face of the shield as the same is propelled 80 forwardly, said co-acting deflector element being flexible.

4. In a device of the character described, an overhead shade element, a substantially flat wind shield element suspended therefrom and near the forward edge thereof, means for securing the same at an angle whereby it will operate as a deflector, and a co-acting deflector element extending underneath the shade element and arranged adjacent the upper part of said shield element and in front of the latter, said co-acting deflector element being curved to start a draft of air down the face of the shield as the same is propelled 95 forwardly, said co-acting deflector element being flexible.

5. In a device of the character described, an overhead shade element, a substantially flat wind shield element suspended therefrom and near the forward edge thereof, means for securing the same at an angle whereby it will operate as a deflector, and a co-acting deflector element extending underneath the shade element and arranged adjacent the upper part of said shield element and in front of the latter, said co-acting deflector element being curved to start a draft of air down the face of the shield as the same is propelled 100 forwardly, with means for adjusting the forward end of the shade element 105 up and down.

110 6. In a device of the character described, an overhead shade element, a substantially flat wind shield element suspended therefrom and near the forward edge thereof, means for securing the same at an angle whereby it will operate as a deflector, and a co-acting deflector element extending underneath the shade element and arranged adjacent the upper part of said shield element and in front of the latter, said co-acting deflector element being curved to start a draft of air 115 down the face of the shield as the same is propelled forwardly, with means for adjusting the forward end of the shade element up and down, said means comprising a brace connected at one end to said shade and having a slot in its other end and a support arranged angularly to the slotted end of said brace and in substantial alignment with the said slot.

6. In a device of the character described, a main support, an overhead shade element carried thereby and projecting forwardly therefrom, a relatively flat wind shield element pivoted to and underneath said shade element and toward the forward edge thereof with means for adjusting said shield element at different angles, a deflector element

co-acting with said shield element and located underneath said shade element and partially overlapping the upper portion of the shield element and curved to start a draft of air downwardly along the face of the machine as the device is propelled forwardly.

GEORGE F. MILES.
SANFORD EVANS.
